(57) **CLAIM**

The ornamental design for a motor vehicle, as shown and described.

DESCRIPTION

FIG. 1 is a top and side perspective view of a motor vehicle showing our new design;

FIG. 2 is a top, front and side perspective view thereof;

FIG. 3 is a top, rear and side perspective view thereof;

FIG. 4 is a right side view thereof;

FIG. 5 is a rear view thereof;

FIG. 6 is a front view thereof;

FIG. 7 is a top view thereof;

FIG. 8 is an enlarged elevational view of part A taken along line 8-8 end in FIG. 4;

FIG. 9 is an enlarged elevational view of part B taken along line 9-9 end in FIG. 4;

FIG. 10 is an enlarged elevational view of part C taken along line 10-10 end in FIG. 4; and,

FIG. 11 is an enlarged elevational view of part D taken along line 11-11 end in FIG. 4.

The claim for a motor vehicle shown in FIGS. 1-7 is shown within the dash-dot broken lines. The dash-dot broken lines and any element shown outside the dash-dot broken lines form no part of the claimed design, but instead are included to show environmental aspects of the claimed design. The dash-dash broken lines shown in FIGS. 8-11 of an inner portion of the motor vehicle are for the purpose of illustrating subject matter that forms no part of the claimed design.
